CLAIM

The ornamental design for an incision tool, as shown and described.

DESCRIPTION

FIG. 1 is a perspective view of an incision tool. FIG. 2 is front elevation view of the incision tool of FIG. 1; FIG. 3 is a rear elevation view of the incision tool of FIG. 1; FIG. 4 is a left side view of the incision tool of FIG. 1; FIG. 5 is a right side view of the incision tool of FIG. 1; FIG. 6 is a top plan view of the incision tool of FIG. 1; and, FIG. 7 is a bottom plan view of the incision tool of FIG. 1. The broken lines in the drawings are for the purpose of illustrating portions of the incision tool that form no part of the claimed design. The dot-dash lines illustrate a boundary that forms no part of the claimed design. Surfaces forming part of the claimed design are defined by shaded surfaces.

1 Claim, 6 Drawing Sheets

Related U.S. Application Data
